(57) **CLAIM**

The ornamental design for a portion of a shoe sidewall, as shown and described.

DESCRIPTION

FIG. 1 is a side view of an embodiment of a portion of a shoe sidewall showing a new design;

FIG. 2 is a front view of a portion of the shoe sidewall of FIG. 1;

FIG. 3 is a front perspective view of a portion of the shoe sidewall of FIG. 1;

FIG. 4 is a rear perspective view of a portion of the shoe sidewall of FIG. 1;

FIG. 5 is a side view of another embodiment of a portion of a shoe sidewall showing a new design;

FIG. 6 is a rear view of a portion of the shoe sidewall of FIG. 5;

FIG. 7 is a front perspective view of a portion of the shoe sidewall of FIG. 5; and,

FIG. 8 is a rear perspective view of a portion of the shoe sidewall of FIG. 5.

Please note that the Figures include broken and solid lines. The area within the solid lines and dot-dash-dot forms the claimed design. The area within the broken lines is environmental. Color, contrast and texture form no part of the claimed design in any of the Figures.

1 Claim, 8 Drawing Sheets
